UNITED STATES PATENT OFFICE.

WALTER A. HEINRICH, OF ST. LOUIS, MISSOURI, ASSIGNOR TO W. N. MATTHEWS CORPORATION, OF ST. LOUIS, MISSOURI, A CORPORATION OF MISSOURI.

ANCHOR.

Application filed November 12, 1925. Serial No. 68,500.

This invention relates to anchors, and with regard to certain more specific features to expanding earth or ground anchors for holding pole stays and the like.

5 Among the several objects of the invention may be noted the provision of an expanding earth anchor which is light and compactly arranged before sinking and expanding thereof; one which may be positively expanded with little effort; one which expands to relatively great limits for a given closed or unexpanded size thereof, thereby exerting a strong hold in the earth; and one which will last and hold indefinitely 10 after sinking and yet, with the stated advantages, will be economical of manufacture and of use. Other objects will be in part obvious and in part pointed out hereinafter.

The invention accordingly consists of the 20 elements and combinations of elements, features of construction, and arrangements of parts which will be exemplified in the structure hereinafter described and the scope of the application of which will be indicated in the following claims.

In the accompanying drawings, in which are shown two of various possible embodiments of the invention,

Fig. 1 is a side elevation showing the application of the anchor to the earth by means of a wrench;

Fig. 2 is a plan view of the anchor with parts broken away;

Fig. 3 is a vertical section taken on line 35 3—3 of Fig. 2;

Fig. 4 is a vertical section taken on line 4—4 of Fig. 2;

Fig. 5 is a side elevation of a gear casting;

Fig. 6 is a plan view of a wrench for the anchor;

Fig. 7 is a side elevation of Fig. 6;

Fig. 8 is a plan view of an anchor plate;

Fig. 9 is a plan view of a modified four-plate form of anchor showing alternate expanded positions of the plates thereof; and

Fig. 10 is a vertical section taken on line 10—10 of Fig. 9.

Similar reference characters indicate corresponding parts throughout the several views of the drawings.

Referring now more particularly to Figs. 1 and 2 of the accompanying drawings, there

is indicated at numeral 1, a round flat casting comprising an upper disc-like face or wall 55 3 and a lower disc-like face or wall 5 (see also Figs. 3 and 4). The walls 3 and 5 are joined together at opposite edges by portions 7 and 9, which portions cause a space 11 to be left between the walls 3 and 5, 60 which space is more or less rectangular in cross-section (see Fig. 4). Cast to the wall 3 is a guide lug 13 which is made about one-half the thickness of the opening 11. It reaches from one edge to approximately the 65 center of the wall. On the other wall 5 is formed another similar guide lug 15, aligned with said lug 13 as to length, but in another plane. The lug 15 is also approximately one-half the thickness of the opening 11, but 70 occupies that plane of the opening which the other lug 13 does not. Therefore in side-ward projection only the upper surface of the guide lug 15 and the lower surface of the lug 13 are coplanar. 75

A hole 17 is formed through the walls 3 and 5 of casting 1, the sides of which the said lugs lead up to or near (Fig. 2).

Slidably placed within the opening 11, between the portions 7 and 9, are two anchor plates 19 and 21. Each anchor plate (Fig. 8) comprises a more or less disc-shaped piece provided with the sideward flats 23 which are adapted to permit relative passage of the portions 7 and 9 of the casting 1. 85 Each plate is approximately one-half the thickness of the opening 11, that is, it is about as thick as one of the said lugs 13 or 15. One rounded edge 25 is sharpened, or at least the plate is tapered down toward 90 said edge.

From the opposite edge 27 is formed a recess or opening 29. This opening is slightly wider than the width of the guide lugs 13 and 15 and reaches centrally such 95 a distance as to meet the hole 17 of the said casting 1 when the plate is inserted into the opening 11 and the recess 29 aligned with one of the guides 13 or 15.

On one side of the opening are formed 100 rack teeth 31. These teeth, as indicated in Fig. 2, do not interfere with the sliding relationship between the openings 29 and said guides, but rather aid in guiding the plates.

It is obvious that both the plates 19 and

21 may be entered into the opening 11 from opposite sides thereof, and each may be entered opposite its respective guide lug, for example opposite lugs 13 and 15 respectively. Each plate is also entered into the opening 11 in the plane of its respective guide lug, and hence the three pieces, namely pieces 1, 19 and 21 may be easily assembled. For purposes hereinafter to be described, the respective sets of teeth on the plates should come on opposite sides of a line such as the line 3-3 (Fig. 2). In order to cause such positive assembly of the pieces, the guides are unsymmetrically arranged on opposite sides of the said center line by the width of the rack tooth depth. Hence no mistake can be made in assembling the pieces. The one side of each of the openings 29 is tangential to the hole or opening 17, as well as is the corresponding side of each lug 13 and 15. The teeth 31 reach their depth into said opening 17 (see Fig. 2). The unsymmetrical cut-away portions 16 of the lugs 13 and 15 accommodate the passage of the said teeth as well as serve the said assembling purpose. It may be noted that each plate 19 and 21, when in the casting 1, rests slidably against the portions 7 and 9, against the other opposite plate, and 30 against the opposite guide lug 13 or 15. It is to be understood that the portions 7 and 9 might act as guides for the plates without the aid of the guides 13 and 15, if desired and properly designed.

35 Now, in order to drive the plates 19 and 21 outwardly to an expanded position, there is rotatably formed in the round opening 17, a toothed casting 33 (Figs. 3 to 5).

The casting 33 comprises circular flanges 35 and 37 which are made to rotatably cooperate with the said walls 3 and 5 respectively. Between the flanges 35 and 37 is integrally formed a gear or pinion 39. The pinion 39 is adapted to engage the sets of rack teeth 31. The lower flange 37 has integrally formed therebeneath a ribbed shoulder 41. The upper flange 35 has formed thereabove a ribbed, preferably square, extension or gudgeon 43. The extension or gudgeon 43 may be made of any suitable polygonal shape, and is properly ribbed for strength. Passing longitudinally and centrally through the casting 33 is a suitable hole 45 adapted to slidably receive there-through a stay bolt 47. The stay bolt 47 is the piece to be anchored in the earth.

60 The operation of the anchor is almost obvious. By applying the bolt 47 to the casting 33 (Figs. 1 and 3) and dropping the anchor, with the bolt 47, into a previously formed hole H, the device is ready for anchoring. To anchor, it is only necessary to turn the casting 33 as indicated by the arrow in Fig. 2 (clockwise) whereupon the upper plate 19 and the lower plate 21 are

fed to the right and left respectively (see Figs. 2 and 3) to assume the dotted line positions shown in Fig. 3. These positions are such as to drive the sharpened edges 25 of the plates into the solid-earth sides of the hole H, thereby permanently anchoring the device. Relative movement between the casting 1 and the casting 33 is accomplished, either by depending upon a frictional effect between the sides of the hole H and the casting 1, or by quickly turning the casting 33, whereby the inertia of the casting 1 is made effective to cause relative motion. Either of these effects need be only slight, in so far as a slight movement outward of the plates immediately binds the casting 1 in the hole H.

In order to bring about turning of the casting 33, a wrench 49 (Figs. 1, 3, 6 and 7) is provided therefor. This wrench 49 comprises a vertical tubular portion 51 provided with a lateral bore 53 for fastening the wrench to a wrench handle 67 (Figs. 1 and 3). Parallel to said tubular portion 51, but offset from its axis and downwardly shaped, is a preferably square socket 55, adapted to loosely fit the upward extension 43 of the gear casting 33. The socket may be made in any desired polygonal shape depending upon the polygonal shape of said extension 43. The side walls 57 of the socket, at the side thereof do not meet, but run parallel to one another to form ears 59. A space 61 is left between said ears of width equal to or slightly more than the bolt 47 to be anchored. Thus the wrench is forked. This space or opening 61 reaches inwardly and intersects the top 63 of the socket 55 to a depth which includes the top center. Ribs 65 for bracing the socket 55 and the tubular portion 51 are provided, below the portion 51 and next to the opening 61. Cross holes 52 are bored through the ears 59 for purposes to be described.

To apply the wrench to the anchor (after the anchor and its bolt 47 are in the hole H) it is only necessary to slip the wrench 49 around the bolt 47 by means of the opening 61. This statement is made, assuming that the wrench may have already been applied to its handle 67. A cross bolt 69 (Figs. 1, 3 and 6) is then applied through the holes 52 and a nut run up thereon. The wrench may then be permitted to descend down over the anchor so that the socket 55 engages the upward extension 43. In so far as the handle 67 is provided with a proper cross-bar 68 at the top thereof for applying torque thereto, the anchor may be expanded by turning, as described. The handle 67, in turning the anchor pinion revolves about the bolt 47.

It may be noted from Fig. 1 that the loose fit of the socket 55 on the extension 43 permits a lateral displacement of the handle 67 whereby the effective lever arm of the cross-

bar 68 is increased. It is to be understood that the cross-bar 68 may comprise two side-ward arms instead of only one as shown. The effective lever arm may generally be increased by the means described, because the holes H into which the anchors are placed usually assume the tapering shape indicated in Fig. 1 after a practical depth has been reached. This effect is due to the wearing away of the top of the hole as the drilling tool operates. The cross-bolt 69 prevents splitting apart of the ears 59, but does not serve to clamp them tightly on the extension 43. Hence after the expanding operation is completed, the wrench 49 may readily be withdrawn and unfastened from around the bolt 47.

A modification of the invention is shown in Figs. 9 and 10 in which the device already described is compounded to provide four instead of two expanding plates. In this form the casting 33 is modified only in that the pinion 39 of the preferred form is lengthened to form a pinion 40 adapted to move four racks of teeth instead of two racks. Four plates are used which are identical in form to the plates 19 and 21 (shown in Fig. 8).

To best understand the form of the casting surrounding the four plates 71, 73, 75 and 77 of the modified form, it need only be seen that it comprises two of the castings 1 formed together. The bottom plate 5 of one casting 1 is molded with the top plate 3 of the other casting 1, that is, after one casting has been rotated relatively to the other through an angle of ninety degrees. It will therefore be recognized that the cross-section shown in Fig. 10 is in most respects a compounding of the cross-sections shown in Figs. 3 and 4, which latter sections are taken at right angles to one another. The compounded casting 81 of the modified Fig. 10 form, therefore comprises a central portion 45 or partition 83, top wall 85, bottom wall 87, guides 89 and 91 formed in the top chamber thus formed, and guides 93 and 95 formed in the bottom chamber thus formed. The said pairs of guides are formed on opposite walls and in a manner hereinbefore described for the preferred form.

Fig. 9 indicates the manner in which the plates spread when the pinion 40 is rotated in a manner hereinbefore described for the pinion 39. The advantage of this modified form is an increased anchor grip, which however, requires a greater turning effort at the handle 67 to bring about.

It is readily discernible that as many of the devices of the preferred form may be compounded together, that is, as may be desired and/or practicable.

It is to be understood that the device may be constructed of cast material entirely without machining, thereby making it economical

of manufacture. It is also desirable to make the parts of stampings under certain conditions, and this may be done without departing from the principles of construction and operation herein incorporated.

In view of the above, it is believed that the various features of this invention will be clear without further elaboration, and it will be seen that with the apparatus herein described, the several objects of the invention are achieved and other advantageous results attained.

As many changes could be made in carrying out the above construction without departing from the scope of the invention, it is intended that all matter contained in the above description or shown in the accompanying drawings shall be interpreted as illustrative and not in a limiting sense.

I claim:

1. An anchor of the class described comprising spaced walls, slidable plates therein, and rotatable means passing through the walls for driving the plates outwardly, said means comprising a pinion meshing with teeth on the plates through which pinion a passage is formed to accommodate the piece to be anchored.

2. An anchor of the class described comprising spaced walls, rotatable means passing through the walls, gear teeth on said means at least at points within the walls, slotted plates adapted to slide between the walls and rack teeth formed in said slots for engagement with said gear teeth.

3. An anchor of the class described comprising spaced walls, rotatable means passing through the walls, gear teeth on said means at least at points within the walls, slotted plates adapted to slide between the walls and rack teeth formed in said slots for engagement with said gear teeth, and guides within the walls for the plates.

4. An anchor of the class described comprising spaced walls, rotatable means passing through the walls, gear teeth on said means at least at points within the walls, slotted plates adapted to slide between the walls and rack teeth formed in said slots for engagement with said gear teeth, and guides within the walls for the plates, said guides cooperating with the slots of the plates.

5. An anchor of the class described comprising spaced walls, rotatable means passing through the walls, gear teeth on said means at least at points within the walls, slotted plates adapted to slide between the walls, rack teeth formed in said slots for engagement with said gear teeth, a gudgeon formed with the rotatable means outside of the said walls for purposes of applying a wrench, and a passage through the gudgeon and rotatable means adapted to removably receive the piece to be anchored.

6. An anchor of the class described com-

prising spaced walls, rotatable means passing through the walls, gear teeth on said means at least at points within the walls, slotted plates adapted to slide between the walls, rack teeth formed in said slots for engagement with said gear teeth, an outside gudgeon formed with the rotatable means

for purposes of applying a wrench, and a rotatable connection between the piece to be anchored and said rotatable means.

10

In testimony whereof, I have signed my name to this specification this 10th day of November, 1925.

WALTER A. HEINRICH.
